UNITED STATES PATENT OFFICE.

JAMES W. FULLER, OF CATASAUQUA, PENNSYLVANIA.

DESIGN FOR A CAR-WHEEL TIRE.

SPECIFICATION forming part of Design No. 28,192, dated January 18, 1898.

Application filed October 27, 1897. Serial No. 656,589. Term of patent 14 years.

To all whom it may concern:

Be it known that I, JAMES W. FULLER, a citizen of the United States, residing at Cata-
sauqua, in the county of Lehigh and State of
Pennsylvania, have invented and produced a
new and original Design for a Car-Wheel Tire,
of which the following is a specification, ref-
erence being had to the accompanying draw-
ings, forming part thereof, in which—

Figure 1 is a perspective view of the tire of
the design of my invention, and Fig. 2 is an
enlarged cross-sectional view of the same on
the line $x x$ of Fig. 1, these two views being
deemed essential or necessary in order to dis-
close the leading feature of my design, which
consists of the particular shape or configura-
tion of the tire.

Referring to the drawings, a represents the
tire-section, having a face or tread a' , which

merges into a curved flange or rim a^2 . On 20
the back or rear side of the tire is provided
an inclined wall or edge a^4 , which merges into
an offset a^5 , the face or edge of which offset
is slightly concaved about a^6 , and from the
said offset is provided an inclined wall or edge 25
 a^7 to the inner side of the tire.

Having thus described my invention, what
I claim as new, and desire to secure by Letters
Patent, is—

The design of a tire for a car-wheel, sub- 30
stantially as shown and described.

In testimony whereof I have hereunto set
my signature in the presence of two subscriv-
ing witnesses.

JAMES W. FULLER.
